UNITED STATES PATENT OFFICE.

ERNEST F. SAYLOR, OF ILWACO, WASHINGTON.

CARBURETER.

Specification of Letters Patent.

Patented Apr. 8, 1919.

1,299,622.

Application filed March 4, 1915. Serial No. 11,962.

To all whom it may concern:

Be it known that I, ERNEST F. SAYLOR, a citizen of the United States, residing in the city of Ilwaco, county of Pacific, and State of Washington, have invented certain new and useful Improvements in Carbureters, of which the following is a specification.

My invention relates to carbureters, and more particularly to certain new and novel improvements therein, whereby I am able to make a variety of adjustments of the various parts thereof, and thereby to get a better regulation and greater efficiency therefrom.

Among the salient objects of my invention are:—to provide in a carbureter an air inlet valve, an oil inlet valve, and a throttle valve, with means for effecting a simultaneous and uniform movement thereof, and with means for adjusting said valves relative to each other and relative to the ports which they control, whereby I am able to most effectively regulate the air and oil inlet passage-ways to the carbureter, and the passage-way leading from the carbureter to the cylinders, so as to secure the best mixture of air and oil for the engine; to provide in a carbureter of the character referred to, means whereby, with a single controlling or operating member, I am able, not only to control the movement of said valves, but with such means I am able by various adjustments of the connections to cause one or two of said valves to move faster or slower than the other, or others, in its, or their, opening or closing operation, and thereby to open or close either before or after the other, or others, as desired; to provide a carbureter case or body in two or more parts or sections, adjustable relative to each other, whereby to conveniently adapt said carbureter for connection with the engine cylinders at various angles; and, in general, to provide a new and improved carbureter of the character referred to which will be practical, efficient and convenient to adjust and manipulate.

In order that others may thoroughly understand my invention, I have shown in the accompanying sheets of drawing one practical embodiment thereof, which I will now describe:

Figure 1 is a vertical sectional view through a carbureter embodying my invention, taken on the line 1—1 of Fig. 3;

Fig. 2 is a similar view at right angles to the view in Fig. 1, taken on the line 2—2 of Fig. 3;

Fig. 3 is a top plan view of a carbureter with a part of the top broken away; 60

Fig. 4 is a horizontal sectional view taken on line 4—4 of Fig. 2;

Fig. 5 is a side elevation of a carbureter embodying my invention with a part of the top broken out; 65

Fig. 6 is a horizontal sectional view through Fig. 2 on the line 6—6 therein;

Fig. 7 is a horizontal sectional view taken on the line 7—7 of Fig. 1;

Fig. 8 is a top plan view similar to Fig. 3, 70 showing a different connection for operating the oil or needle valve, and

Fig. 9 is a fragmentary, vertical sectional view showing a slight modification in the connection for operating the needle valve. 75

Referring now more in detail to the drawing, the carbureter here shown for the purpose of illustration, comprises a cylindrical body composed of the lower section A, an upper section B, and a top, or cover, C. 80 Referring to Figs. 1 and 2, the lower portion of the section A has an annular water jacket A¹, an annular air chamber A², with a cylindrical wall member A³, having a plurality of inlet ports A⁴ therein, with a main air-inlet A⁵ at one side, leading through the water jacket A¹ to the annular air chamber A². Rotatably mounted within the cylindrical wall member A³, is a cylindrical air-inlet valve A⁶, having a plurality of air-inlet ports A⁷, adapted to be moved into and out of register with the ports A⁴ in said cylindrical wall member A³. Said air-inlet valve is provided with a central operating shaft A⁸, upon the upper end of which is mounted 90 a laterally projecting operating arm A⁹. Said air inlet valve A⁶, is open at its upper end so that air passing in through the inlet A⁵, the ports A⁴ and A⁷ will pass upwardly into a mixing chamber A¹⁰ in the upper portion of the section A. Formed in the outer part of said upper section is an annular oil chamber A¹¹, having mounted therein a float A¹², of cork or other suitable float material, supported at one side by an arm A¹³, pivotally mounted at A¹⁴, in an extension chamber A¹⁵, on the side of the body, and adapted 100 to automatically move an oil inlet valve A¹⁶, which controls the inflow of oil to the annular oil chamber A¹¹. The annular oil 110

105
110

chamber A¹¹, is connected from one side to the other by a cross member A¹⁷, having therethrough a passage-way A¹⁸, and provided on its top surface with an oil puddle 5 or needle valve cup, A¹⁹, having a central port A²⁰, opening down into said passage-way A¹⁸, whereby the oil from the annular oil chamber A¹¹ rises through said passageway A¹⁸, and the port A²⁰ into the puddle A¹⁹.

The upper section B of said carbureter also comprises an outer annular water jacket B¹, an annular chamber B², with a cylindrical wall member B³, having ports B⁴ there- 15 through. The lower end of said cylindrical wall member B³, is provided with supporting arms B⁵, for supporting a lower bearing plate member B⁶, above said puddle, A¹⁹, substantially in the manner indicated. Rotatably mounted within said cylindrical wall member B³, is a cylindrical throttle valve member B⁷, having ports B⁸, therein, adapted to be moved into and out of register with the ports B⁴ in said cylindrical wall member B³, said cylindrical throttle valve member B⁷ being closed at its upper end and provided with a bearing sleeve B⁹, and being open at its lower end.

The body section B, fits upon and over 30 the annular oil chamber A¹¹, with an annular holding flange B¹⁰, fitting down into the chamber A¹⁰, to hold said parts together, and whereby to make the part or section B, adjustable circumferentially upon said lower section A, to bring the main outlet B¹³ to a desired angle for connection to the engine.

Mounted through the sleeve B⁹ of the cylindrical throttle valve member B⁷, is an operating sleeve B¹¹, which extends through 40 said throttle valve member and has a bearing at its lower end in the plate B⁶, just above the oil puddle A¹⁹. Said operating sleeve B¹¹ is rigidly connected by means of an arm B¹², extending out around said plate B⁶, and the puddle member A¹⁷, to the arm A⁹, upon the upper end of the shaft A⁸. Said operating sleeve B¹¹, turns within the sleeve B⁹, of the cylindrical valve member B⁷ so that when the said sleeve member B¹¹ is oscillated about its own axis it operates to turn the air inlet valve A⁶ below. A needle valve B¹⁴ extends through the sleeve B¹¹, and has its lower end tapered to fit into the port A²⁰ for controlling the flow of the oil from the 50 annular oil chamber through the passage-way A¹⁸, and thence through said port A²⁰ to the puddle A¹⁹, where it is exposed to the air passing upwardly through the chamber A¹⁰.

I will now describe the operating mechanism whereby said air inlet valve A⁶, said throttle valve B⁷, and said needle valve B¹⁴, are manipulated to control and regulate the 60 passage of air up through the carbureter and around the oil puddle A¹⁹. Mounted

upon the upper body section B, is a plate C', through an opening in the center of which the sleeve B⁹ works, and through this sleeve B⁹, the operating sleeve B¹¹, and the needle valve B¹⁴ project. A fixed arm C², is mounted 70 upon plate C', and projects upwardly and inwardly over the center of said plate, and constitutes a bearing support for the upper end of the sleeve B¹¹, and the needle valve B¹⁴. To this end, said arm C² is provided at its upper end with a threaded hub-like portion within which turns an externally threaded smaller hub member C³, having a short arm C⁴, and secured to the upper end of the needle valve B¹⁴, so that as 80 said arm C⁴ is turned, it is raised or lowered by reason of the threads in the hub of the fixed arm C², thus also raising and lowering the needle valve B¹⁴ out of and into the oil inlet port A²⁰, to the oil puddle A¹⁹, to control the inflow of the oil. The upper end of the sleeve B¹¹ simply has a holding bearing in the under side of the fixed arm C², 85

The upper end of the sleeve B⁹, formed as a part of the throttle valve B⁷, is provided 90 with an operating arm C⁵, having an adjustment slot C⁸ in its outer end. The upper end of the sleeve B¹¹ is also provided with a similar operating arm C⁷, having an adjustment slot C⁶ in its outer end.

A main operating arm D is extended into the upper casing or cover C, and has a pivotal bearing at D', around the upper portion of the hub of the fixed arm C². The short arm C⁴, upon the upper end of the needle valve B¹⁴, has a loose pin connection with the arm D, as at D², whereby as said arm D is moved sidewise, short arm C⁴ is also moved to turn said needle valve, and to raise and lower the same by reason of the threaded connection through the arm C². A pair of toggle links D³—D⁴, connect the arm D, as at D⁵, to the outer end of the arm C⁵, being adjustably connected therewith in the slot C⁸. A pair of toggle links D⁶—D⁷, also connect said main lever D, at D⁵, with the outer end of the arm C⁷, being adjustably connected therewith in the slot C⁶. A spring member C⁹, attached to the upturned portion of the arm D, bears outwardly at its opposite ends against the links D⁶ and D⁷, as shown in Fig. 3.

Two bearing cam members E¹—E², are pivotally mounted upon the plate C' in position to bear against the toggle links at 120 their joints, which may be provided with anti-friction rings D⁸—D⁸ in the manner indicated. Said bearing cams have curved bearing surfaces and can be adjusted inwardly or outwardly, by means of thumb screws, E³—E⁴, so as to be concentric with the pivotal bearing of the operating mechanism, or so as to be eccentric to said pivotal bearing, thus causing said toggle links at 125 their joints to be moved according to the ad- 130

justment of the cam bearing members E^1 and E^2 . If the cam bearing members E^1 and E^2 are adjusted so that their bearing surfaces stand concentric with the center of the 5 needle valve, which is the center of the operating mechanism, then the parts of the toggle links will maintain their relative angular positions as the operating lever D is moved, but if said cam bearing members E^1 10 and E^2 are adjusted so that their bearing faces are not concentric to the center of the operating mechanism, but are eccentric thereto, then as said main operating lever D is moved in one direction or the other, 15 said toggle links will tend to straighten, or move together, as the case may be, in addition to their general movement. This is because the joints in said toggle links bearing against the cam bearing members E^1 — E^2 , 20 will be moved inwardly, or permitted to move outwardly, by reason of the position of the cam bearing members. This operates to move the arms C^7 and C^5 in opposite directions, either uniformly with the movement 25 of the lever D , as when the cam bearing members are concentrically adjusted, or faster or slower than said operating lever D , depending upon the adjustment of said cam bearing members. Stops D^a and D^e , may be 30 provided to limit the extreme movements of the operating lever D , as indicated in Fig. 3.

In Fig. 3 the main operating lever D , has a direct, positive connection with the needle valve through the short arm C^4 , and the air inlet valve and the throttle valve have a variable connection with said operating lever D by reason of the toggle links, arms C^7 and C^5 , and the cams E^1 and E^2 . In Fig. 8, I have connected the main operating lever D , 40 directly to the throttle valve, and have turned the short arm C^4 around a quarter turn, and connected it to the arm C^e , whereby by the air inlet valve, operated by the arm C^5 , and the needle valve, operated by the 45 short arm C^4 , which is directly connected to the arm C^e , have the variable connections, while the throttle valve has a direct connection, with said operating arm D .

In Fig. 9, I have shown a slight change in 50 the connection for operating the needle valve. Instead of turning the threaded hub portion C^s , and the needle valve B^{14} , upon which it is mounted, by means of the operating lever D , as in Figs. 1 and 3, I have provided the operating lever D , at its connected end, with a threaded hub, adapted to turn on the smaller threaded hub C^s , upon the needle valve B^{14} , whereby to lift said needle valve without turning it, together with the short 55 arm C^4 and its holding pin D^s , which has a holding, adjustable connection with the upper end of the fixed arm C^a , which is made as clearly indicated in said Fig. 9.

The water supply, for the water jackets 60 A' — B' , is connected thereto, as at 2—2, and

said water jackets are connected to communicate with each other by means of a bypass pipe at 3—3.

The extension A^{15} , on the side of the carburetor body is provided with a removable 70 plug 4, to afford access to the interior thereof, for adjusting the oil inlet valve A^{16} , which is operated by the float A^{12} .

The operation of the invention may be 75 briefly described as follows:

Assuming that the parts are assembled as illustrated in Figs. 1 to 4 inclusive, the air inlet valve A^e , the needle valve B^{14} , and the throttle valve B^7 , will all be approximately 80 half open, as illustrated in Fig. 4, in which the ports A^7 , of the air-inlet valve A^e , are shown to be about half in register with the ports A^4 , of the cylindrical wall member A^3 . In this position the air passes into the carburetor through the main inlet opening A^5 , 85 through the ports A^4 and A^7 , up through the chamber A^{10} , around the oil puddle A^{19} , and upwardly into the throttle member B^7 , and thence through the throttle B^{13} to the engine. The arm C^5 , which operates the 90 throttle valve B^7 , and the arm C^7 , which operates the air-inlet valve A^e , through the operating tubular member B^{11} , can be so adjustably connected to the toggle links, D^4 95 and D^7 , by reason of the slots C^6 and C^8 , therein, that they can be opened and closed together, or a limited variation can be made through the connections to said links, whereby one or the other will open in advance of the other.

If it is desired that one or the other of 100 said arms, C^7 and C^5 , should be moved faster or slower than the other, this may be accomplished by adjusting the thumb screws E^3 or E^4 , so as to move the cam bearing members E^1 or E^2 inwardly, or outwardly, as hereinbefore referred to. For example, if thumb screw E^4 , is turned so as to move the cam member E^2 inwardly, it will tend to straighten the toggle links D^3 110 and D^4 and thereby move the arm C^7 , which operates to turn the air-inlet valve A^e slightly, and as the bearing surface of this cam member E^2 would be more or less eccentric to the pivotal axis of the arm C^7 , and the operating lever D , this would operate to vary the movement of the arm C^7 , relative to the movement of the operating lever D , the difference being compensated for 115 through the relative movements of the toggle links D^3 and D^4 . Thus I am able, through the connections from the air inlet valve A^e , and the throttle valve B^7 , and the needle valve B^{14} , to the main operating lever D , to operate said air-inlet valve A^e , and the 120 throttle valve B^7 , and the needle valve B^{14} , together at the same speed, or at different speeds, or to adjust their connections so that one will commence to open before the others, if desired, and thus to regulate the amount 125

130

of air passing through the carbureter, whereby to secure the best mixture of the air with the oil, or gasoline.

If it is desired that the variable movements and adjustments should be made possible in the needle valve and the air-inlet valve, instead of the throttle valve and the air-inlet valve, I can connect the main operating lever D direct to the throttle valve, 10 as indicated in Fig. 8, and can connect the needle valve arm C⁴, and the air-inlet valve C⁷, to the toggle links, D⁴ and D⁷, as indicated. Thus I can vary the operating connection from the operating lever D, to the 15 needle valve, which controls the oil inlet, and to the arm C⁷, which moves the air-inlet valve, so as to get the right adjustment between the air inlet openings and the oil supply, and have a direct movement with 20 the operating lever D, of the throttle valve, which controls the passage of the mixture from the carbureter to the engine.

Attention is called to the arrangement in 25 which the bearing plate B⁶, is supported slightly above the oil puddle A¹⁹, so as to leave a thin disk-like space there between, past the edges of which the air passes in its upward movement, picking up the thin film of oil as it passes. There is also a more effective suction action, so to speak, acting to 30 draw the oil up into the oil puddle, for the reason that the oil is more effectively picked up and carried from around the edge of the narrow space between the member B⁶, and the puddle A¹⁹, than it would be from an open uncovered puddle of oil.

Attention is also called to the fact that the ports controlling the inlet of the air into 40 the carbureter, and the ports which control the outlet therefrom, or the suction action, so called, applied to the carbureter at the outlet B¹³, by the action of the engine, must be regulated as to their relative areas, in order to get the best results. The more of 45 the vacuum effect created in the carbureter will, of course, tend to cause the oil to rise therein, and to be sucked up, so to speak, by the air which is rushed through the carbureter, under the suction action caused by 50 the movement of the pistons in the engine cylinders.

I am aware that changes can be made in the embodiment in my invention as shown for purpose of illustration without departing 55 from the spirit thereof, and I do not, therefore, limit my invention to the particular showing here made, except as I may be limited by the hereto appended claims.

I claim:

60 1. A carbureter of the character referred to comprising in combination a two-part casing, the parts of which are adjustable relative to each other about a common axis, an inlet valve in one part of said casing, 65 an outlet valve in the other part of said

casing, said valves being arranged concentric with each other, an oil puddle in said casing, means for supplying oil to said oil puddle, an oil valve arranged concentrically with said outlet valve and said inlet valve 70 for controlling the supply of oil to said puddle, an operating member having operating connections for turning said inlet, outlet and oil valves about a common axis to control the passing of air through said casing 75 and the supply of oil to said puddle, and independent means for regulating the movement transmitted by said operating member to said valves without changing the connections therewith, substantially as described. 80

2. In a carbureter of the character referred to, a casing having a passageway therethrough, a cylindrical inlet valve for controlling the admission of air to said casing, a cylindrical outlet valve arranged concentrically with said inlet valve, said valves having openings through their sides, an operating member with operating connections for simultaneously turning said inlet and 90 outlet valves in both directions about a common axis to regulate the passage of air through said casing, and means for regulating the relative amount of movement transmitted by said operating member to 95 either or both of said inlet and outlet valves.

3. In a carbureter, a casing, an inlet valve and an outlet valve for controlling the passage of air therethrough, an oil puddle with means for supplying oil thereto, an oil 100 valve for controlling a supply of oil to said puddle, an operating lever with operating toggle connections therefrom to said inlet, outlet and said oil valves for simultaneously operating the same in either direction by the 105 movement of said operating lever, and means operating on the toggle connections from said operating lever to said valves for changing the movement transmitted to said valves by the movement of said lever without changing the movement of the latter, 110 substantially as described.

4. In a carbureter, in combination, a casing with an passageway therethrough, an air inlet valve and an outlet valve arranged 115 concentrically with each other in said casing for controlling the passage of air therethrough, an oil puddle with oil valve for controlling the supply of oil thereto, an operating lever with toggle-link connections 120 therefrom for operating said valves, and adjustable bearing members with means for adjusting the same relative to said toggle-links, whereby to regulate the movement transmitted from said operating member to 125 said valve members relative to the movement of said operating member, substantially as described.

5. In a carbureter having controlling 130 valves for regulating the air and oil supply

- thereto, and therefrom, a main operating member, operating toggle connections therefrom to said several controlling valves, and cams operating on said toggles for causing 5 a variable relative movement of one or more of said valve members without changing the connections thereto, as said main operating member is moved to simultaneously operate said valves.
- 10 6. A carbureter comprising in combination a casing having inlet and outlet openings, an oil puddle therein, means for supplying oil thereto, an air inlet valve, a throttle valve interposed between said puddle and said outlet, a needle valve for controlling the oil supply to said puddle, a main operating member, operating toggle connections therefrom to said inlet valve, said needle valve, and said throttle valve, 15 whereby to operate said valves simultaneously, and adjustable cams operating on said toggles for causing variable movements in some of said valves, as said main operating member is moved.
- 20 7. A carbureter of the character referred to, comprising a casing having an air inlet near its bottom and an outlet near its top, a cylindrical, concentrically disposed air
- inlet valve for controlling the air inlet, a cylindrical, concentrically disposed throttle 30 valve for controlling the outlet from said casing, an oil chamber in said casing, a valve controlling the oil supply to said oil chamber, a float attached to said valve for operating the same, an oil puddle concentrically disposed in said casing with supply connection through its bottom from said oil chamber, a needle valve controlling said supply communication to said oil puddle, an operating lever with operating connections 40 for positively moving said air inlet valve, said throttle valve and said needle valve simultaneously in either direction, and means for adjusting and regulating the operating connections from said operating 45 lever to said valves, whereby different movements can be imparted to different valves through the simple movement of the operating member, substantially as described.

Signed at Ilwaco, Washington, this 26th 50 day of February, 1915.
